UNITED STATES PATENT OFFICE.

WILLIAM LAMBERT WHITE, OF HEDON, ENGLAND.

APPARATUS FOR SUGAR-COATING CONFECTIONERY.

SPECIFICATION forming part of Letters Patent No. 658,168, dated September 18, 1900.

Application filed April 30, 1900. Serial No. 14,899. (No model.)

To all whom it may concern:

Be it known that I, WILLIAM LAMBERT WHITE, a subject of the Queen of Great Britain, residing at Hedon, near Hull, in the county of York, England, have invented new and useful Improvements in Apparatus for Crystallizing Gums, Fondants, and Sweets of a Like Nature, of which the following is a specification.

10 This invention relates to the crystallizing of fondants, gums, and sweets of a like nature which require a coating of sugar upon them.

In the system at present in vogue for crystallizing sweets the sugar is boiled with water 15 in an ordinary vat until it becomes a syrup and is then run or ladled into a number of tanks or other receptacles to cool, as to obtain the most satisfactory results it must only be run onto the goods to be crystallized 20 when in a cold or almost cold state. When the syrup has cooled sufficiently, it is transferred, as a rule, by ladling into the dishes which contain the sweets, the dishes most generally in use being similar to the ordinary 25 domestic dripping-tin, but being sometimes provided with a spout or other suitable outlet which is kept corked or closed until it is required to run off the superfluous syrup. It will therefore be seen that the above process 30 entails a considerable amount of manual labor, as during the various stages the syrup has to be transferred by hand to the different utensils, and the handling of the dishes where large quantities of sweets are made necessi- 35 tates the employment of a large number of hands or operators.

The object of my invention is to construct or provide a plant which will perform the whole crystallizing operation with very little 40 attention, one person being able to attend to one or several sets of plant.

Figure 1 represents a front view of my improved apparatus for crystallizing sweetmeats. Fig. 2 represents a side view, and Fig. 45 3 is a plan view. Figs. 4 and 5 represent a side view and plan view, respectively, of one kind of basket or container which I employ for holding the sweetmeats to be crystallized.

For the purpose of my invention I employ 50 a large cooking and cooling vat or pan A, provided with means for heating it, such as a coil B, and also having internal stirrers C,

Fig. 1, operated by means of bevel-gearing D or other suitable device. The coil B is connected to a steam-pipe E for supplying steam. 55 Also such coil may be connected, if desired, to a water-pipe for supplying cold water, so that such cooking-pan may be employed not only for cooking the syrup, but for cooling it after it is sufficiently cooked. In place of 60 employing the cooking-pan as a cooler also a separate vessel F may be employed for that purpose, such cooling vessel being provided with a coil G, connected to a cold-water-supply pipe H. The said cooling vessel is pref- 65 erably elevated on a stand F to allow of its contents when sufficiently cold being run off through an outlet-pipe I, provided with a suitable cock or cocks J, into another vessel or vessels K, which I call "syrup-baths," and un- 70 derneath each syrup-bath K or in any other suitable position I place a collecting-tank L, the syrup-bath K being provided with a draw-off cock V.

I employ a pump M of any suitable con- 75 struction. This pump M has pipe connec- tions N' N to the cooking-pan A and the collect- ing-tank L, respectively. These pipe connec- tions N' N are for drawing from such tanks. Also the pump has supply-pipes O O 80 to the cooking and cooling tanks for pump- ing the syrup into those tanks, and a dis- charge-pipe P, Fig. 1, may be employed for conveying the used syrup from any one of the vessels to any desired part of the build- 85 ing. The supply-pipes O O may be connected to the pump-pipe and operated by means of a two, three, or four way valve or cock R, or they may each be provided with a separate cock. The pump draws the liquid from the 90 vessel L through the pipe N and delivers it into the vessel A. The pump also draws the liquid from the vessel A through the pipe N' and delivers it into the vessel F. When the 95 cooling as well as the cooking is effected in the vessel A, the vessel F serves as a reser- voir for the cool syrup.

Each tank may be provided with a steam-jet S for steaming-out purposes, thus allowing for the removal of any syrup which may 100 have solidified, and so adhered to the sides of such tanks. Also, if desired, each pipe and cock may be provided with a small steam-jet T for a like purpose, such jets and steam-

pipes being connected in the most suitable manner to the steam-supply pipe S. The said stand F supports the tanks F, K, and L at the required elevations with respect to each other.

The operation of crystallizing is as follows: The sugar is put into the cooking-pan, which is heated by means of steam supplied in any suitable manner. After the sugar is heated to the desired temperature the supply of steam is cut off, and if the pan is used also as a cooling vessel cold water is introduced into the coil or the like and cools the contents of the pan. If used as a cooking vessel alone, which I prefer, the syrup is pumped out of such cooking-pan into the cooling vessel and the cold water run through the coil in such vessel, the water in its passage through the coil quickly cooling the contents of the vessel. When the cooking-pan is employed also as a cooling vessel, it is elevated to the position of the pan F, which is dispensed with. The baskets containing the sweets are placed in the syrup bath or baths and when the syrup in the cooler is sufficiently cool the required quantity is run into the bath or baths to cover the baskets contained therein. After the baskets and their contents have been submerged for the required time the syrup is

run off through the outlet-cock into the collecting-tank, whence it can be raised by means of the pump to the cooking-pan again or to other pans in connection with other sets of plant, and the operation is continued, as before described. The syrup after being reused until too weak or unsatisfactory for crystallizing purposes is pumped away to any part of the building to be used for any other purpose for which it would answer.

What I claim as the invention, and desire to secure by Letters Patent, is—

The combination, with a pan F for cool syrup, of a syrup-bath K arranged at a lower level than the pan F, baskets for holding the articles to be coated in the bath K, a collecting-tank L arranged at a lower level than the syrup-bath K, valved pipe connections between the pan F, bath K and tank L whereby the syrup is run from one vessel to another by gravity, and means for supporting the said pan, bath and tank at different elevations, substantially as set forth.

In testimony whereof I affix my signature in the presence of two witnesses.

WILLIAM LAMBERT WHITE,
